UNITED STATES PATENT OFFICE.

DENNIS W. SMITH, OF WILMETTE, ILLINOIS, ASSIGNOR TO COLBORNE MANUFACTURING COMPANY, OF CHICAGO, ILLINOIS, A CORPORATION OF ILLINOIS.

PIE-MAKING MACHINE.

Application filed September 14, 1925. Serial No. 56,282.

This invention relates to pie making machines and in particular to means for ejecting the completely formed pie from the machine.

5 The main objects are to provide ejecting means which is adapted to function without any interruption in the operation of the machine; which is adapted to coact with moving pie holders and act in synchronism with 10 the same; which is reliable in its action; and to provide means in the ejector for avoiding accidental damage to the machine.

An embodiment of this invention is shown in the accompanying drawings, in which:—

15 Figure 1 is a plan view showing the ejector mechanism mounted at the end of the pie forming machine.

Fig. 2 is a fragmentary section taken on the line 2—2 of Fig. 1.

20 Fig. 3 is an enlarged fragmentary section on line 3—3 of Fig. 1.

Fig. 4 is an end elevation of the slide shown in Fig. 1.

25 Fig. 5 is a plan view of the end of the slide with parts in changed position.

For convenience the term pie, as used herein, includes the pie tin in which the pie is made since the pie and tin are handled as a unit.

30 In general, means are provided to lift the pie vertically from the pie holder, and then the ejector fender which is mounted on a slide sweeps the pie to one side where it is usually received on the conveyor of some other machine.

35 As shown in the drawings, the pies 1 are set in holders 2 which are doweled in position on the plates 3. The plates 3 are carried on each alternate knuckle pin 4 in the 40 vertically jointed chain 5. At the same joints the chain 5 is provided with laterally disposed rollers 6, which, in the side portions of the machine, ride on the support rails 7. But at the end of the pie machine the rails 7 45 are terminated and the chain is supported by the forks 8 on the horizontal sprocket wheel carrier 9.

The wheel 9 is mounted in an extension 10 of the main frame 11 of the pie machine and is constantly driven, and hence moves the chain 5 continuously, by means of the worm 50 12 which meshes with the worm gear 13 on the lower end of the sprocket wheel shaft 14. The holder forms 2 support the flanges

14 of the pie-tins 1 with a space under the 55 bottom of the tin, in which the ejector or lifting plate 15 normally lies on the upper surface of disc 3 with the rod 16 which is attached to the plate 15 extending loosely through the knuckle pin structure 4 and 60 protruding at the lower end thereof.

At the end of the machine shown, the plates 15 are raised to lift the pies 1 out of the holders 2, by means of the circular cam track rail 17 which bears up on the lower 65 protruding end of the rod 16. The track 17 is semi-circular and lies directly under the pitch circle of the end turn of the carrier chain 5 and has downwardly sloping bevel portions at the ends and is connected by the 70 brackets 18 to the outer rails 7 for support. The beveled end portions of 17 are provided for gradually raising and lowering the plate 15.

For moving the pie off the raised plate 15 75 a member 19 carried by a slide 20 is moved across the path of travel and is timed to contact with the edge of a pie, which at that point is raised out of the holder, and sweeps the pie to one side, where it may be 80 received on some such means as the conveyer 21, shown in dotted lines in Fig. 1 and Fig. 2.

The slide 20 is carried in the inverted groove 23 in the guide bar 24 and is marginally supported therein by the guide plates 85 25 secured to the bar 24. The guide bar 24 is supported above the center of the wheel 9 by the horizontal plates 26 and 27 which are bolted to the arms 28 of the frame extension 10.

90 The slide 20 is reciprocated by means of the oscillating bar 28 which has a slot 29 in which is engaged the roller 30 mounted on the under side of the slide 20. The opposite end of the bar 28 is pivoted to the extension 31 of the plate 27 through the hinged link 32. The bar 28 is driven by the crank pin 33 in the crank arm 34 which is rotatably mounted in the frame member 10 with a pinion 35 driven by a gear 36 on the sprocket 100 wheel shaft 14.

95 As shown the slide 20 is positioned to move across the line of travel of the pie holder at a point where the pie is raised from the holder, and the timing relation is such 105 that the slide coacts with each holder as the holder passes its station.

The pusher member 19 comprises the arcu-

ate portion 37 and the lower member 38 which is inclined to engage under the edge of the pie-tin 1. And the pusher 19 is yieldingly hinged to the end of the slide 20 in the following manner: The pusher 19 is attached by means of the slotted bracket 39 (Fig. 2) to the plate 40 carried on the end of the bar 41 (Fig. 5) which underlies and is pivoted to the laterally extending bar 42 by the bolt 43. On the end of the bar 42 is riveted the short plate 44 (Fig. 4) through which the bar 42 is attached to the slide 20 by means of the screws 45. The stop finger 46 attached to the lower bar 41 is yieldingly held against the edge of the support bar 42 by means of the spring 46 which is attached to a port 47 carried in the arm 48 fixed on the support bar 42.

Generally described, the empty pie-tins are placed in the continuously moving holders 2 and the pie is made therein, that is, the lower crust, the filling and the top crust are placed and the crusts trimmed, before the pie reaches the end of the machine shown in Fig. 1. It is then desired to remove the finished pie from the machine without interrupting the travel of the same. The holders, fastened to the chain 3, pass beyond the end of the track support 7, on the near side of Fig. 1, and are engaged by the forked arms 8 of the end wheel 9 which then support the chain and also drive it. As each of the holders leave the track 7, the lower protruding ends of the rods 16 ride up on the cam track 17 and thereby the pie is raised out of the form 2 and held in raised position as it travels near the station of the pusher 19.

When a pie is in front of the pusher 19 the pusher is moving outwardly from its innermost position and engages the edge of

the pie and sweeps it laterally from the machine.

In case a pie is caught in the form 2, or in any case that the pusher strikes an unyielding obstruction, the pusher support hinge at 43 allows the slide 20 to continue its motion and avoid damage to the machine.

The pies are removed in a continuous and efficient manner with suitable safe guarding provisions so that accidental delays are avoided. Also the pie, without injury thereto, may be deposited on any suitable conveying means.

While but one embodiment of my invention has been shown it is considered capable of many alterations and omissions without departing from the spirit of the same.

I claim:

1. In combination in a pie machine having continuously travelling pie holders, a transversely mounted slide, a pusher member pivotally mounted on said slide and yieldingly held in forward position, means for raising a pie out of the holder and into position for engaging with said pusher.

2. In combination in a pie machine having a horizontal conveyer chain provided with pie supports and a sprocket wheel for driving the conveyer chain, a slide having a pusher member mounted to move across the conveyer chain and having a projecting roller, a rotatably mounted crank geared to the said sprocket, an oscillating bar hinged to the machine and pivoted to said crank and having a slot engaging said roller, means for raising the pies into the path of said pusher, and means for driving said sprocket wheel.

Signed at Chicago this 2nd day of Sept. 80 1925.

DENNIS W. SMITH.
